UNITED STATES PATENT OFFICE.

ARTHUR L. STANFORD, OF CHICAGO, ILLINOIS.

CAR-SEAL.

989,438.

Specification of Letters Patent. Patented Apr. 11, 1911.

Application filed May 20, 1910. Serial No. 562,393.

To all whom it may concern:

Be it known that I, ARTHUR L. STANFORD, a citizen of the United States, residing at Chicago, in the county of Cook and State 5 of Illinois, have invented certain new and useful Improvements in Car-Seals, of which the following is a specification.

The car seal of the present invention relates to that type ordinarily used on freight 10 cars and the like, and is affixed to the lock upon the door thereof, and serves as a means to detect when the lock has been tampered with.

The objects of the present invention are, 15 to produce a seal which will be easy of application and removal without the use of any specially designed implement therefor; which will present a surface of sufficient area to receive figures or symbols; when 20 positioned, will be held in a secure and permanent manner and will not be displaced by the movement of the car or through any rough handling which it might receive during ordinary usage; which is capable of being 25 applied in a minimum space of time; which will not require any undue amount of force to effect the application thereof; which will not have any portion thereof attached to the car in a permanent manner; 30 which will require no change in the ordinary lock used on the car door in order to apply the device; and which cannot be removed without being destroyed and rendered unfit 35 for further use. This destruction can be effected in a minimum amount of time and without the use of any special tool.

In the drawings, Figure 1 is a view showing the seal in operative position; Fig. 2, a perspective showing one end of a headed 40 wire inserted within the seal body and the other end of the wire extending out therefrom; Fig. 3, a face view of the interior of one section of the seal; Fig. 4, a longitudinal section of the completed seal before the wire 45 is inserted therein; Fig. 5, a view similar to Fig. 3, showing a wire partially inserted therein; Fig. 6, a longitudinal section of the parts shown in Fig. 5; Fig. 7, a view similar to Fig. 3, showing a wire fully inserted in 50 position; Fig. 8, a longitudinal section of the parts shown in Fig. 7; and Figs. 9, 10, 11 and 12, views showing modified forms of construction.

The seal comprises companion sections 13 55 and 14, each of like size and configuration and formed preferably of earthenware ma-

terial. Each of the sections has a chamber 15 formed in the interior thereof, and, as shown in the construction set forth in Figs. 3 to 8 inclusive, the walls 16 of said chamber are formed on curves, the arcs of which extend in opposite directions to one another. The chamber, as shown, is of an oval shape, with its outer contracted ends 17 forming a mouth or opening and its inner 60 contracting end merging into a recess or pocket 19, which is approximately of the same depth as the depth of the chamber, and is in fact a portion of the chamber 15. The inner ends 19^a of the walls 16 of the chamber are partially cut away to produce companion protuberances or ledges 20. 65

The sections 13 and 14 are each provided with a protuberance 21, which lies adjacent to the mouth of the chamber 15 and extends 70 thereinto; and said protuberance, as shown in Figs. 3 to 8, is of a tapered formation to provide faces 21^a, which extend parallel to the walls 16 of the chamber 15 and are spaced apart therefrom a sufficient distance 75 to permit of the insertion therebetween of the headed end of a wire. The protuberance 21 and the protuberance or ledge 20 co-operate with the walls 16 of the chamber 15 80 to form a channel 22, which guides the passage of the headed end 23 of a wire 24 during the insertion of such headed end into the interior of the seal. 85

As will be seen by referring more particularly to Figs. 5 and 7, when the headed 90 end of the wire is inserted within the mouth 15, it is deflected by the faces 21^a of the protuberance 21 and travels within the curved recess between said face and the wall 16, thus curving the body portion of the wire. 95 When the headed end strikes that portion of the wall 16 which has been partially cut away to form the ledge or protuberance 20, it will be deflected back toward the center of the seal by the curve of said wall, as 100 shown in Fig. 5; and when the headed end has passed by the protuberance or ledge 20, to permit it to enter the pocket or recess 19, it will be sprung into the position shown in Fig. 7, by reason of the resiliency which 105 has been generated in said wire by the curving of the body portion during the insertion of the headed end into the pocket or recess. The ledge 20, being of less depth than the depth of the channel, the body portion of 110 the wire will lie over the surface thereof when the headed end springs into the posi-

tion shown in Fig. 7, and the headed end will lie in the pocket or recess 19 and behind the protuberance, and thus the wire will be held in a manner to prevent its retraction 5 from the interior of the body of the seal by a direct pull outward; and in order to retract the wire from its locked position it will be necessary to spring the headed end toward the center of the seal body and clear 10 of the protuberance or ledge 20, and this will be impossible because the wire will be bent around the protuberance 21 and locked against movement, holding the body of the wire out of direct alinement with the headed end by its contact with the wall of the mouth 15 and the wall of the protuberance 21, so that any movement of the wire tending 15 to swing the headed end in would be checked.

20 The wire may be provided, if desired, with an enlarged portion 23^a, which, when the head is fully inserted, lies within or adjacent to the mouth 15 of the chamber and prevents the insertion of any tool there- 25 into to move the headed end of the wire out from its position behind the ledge or protuberance 20, and also prevents the wire from being cut outside of the seal and the cut end afterward inserted into the seal in 30 a manner to escape easy detection. Thus, when each headed end of the wire is inserted in position as shown in Fig. 7, displacement of the seal from the object through which the loop portion has been 35 passed will be impossible without a cutting of the wire or a breaking of the seal body, both of which operations would cause the seal to have the appearance of being tampered with, so that the person inspecting the 40 seals of the car would recognize that fact.

The sections 13 and 14 are formed with notches or grooves 25, which weaken the sections at one point, so that a blow thereon will break them and permit the wire to be 45 withdrawn from its locked position. As will be seen more clearly in Figs. 5 and 7, if the seal is broken along the line of the grooves 25, the lower or upper portion thereof will be removed from position and the wire 50 readily extracted from the remaining portion. Hence, in the operation of securing and unfastening the seal, no special tool of any form or description is necessary to effect the securing or unfastening thereof.

55 In Fig. 9, a modified structure is shown, in which a seal body is provided with oppositely disposed channels 26; and in Fig. 10 is shown a construction in which a single channel 27 is employed, into which both ends of 60 the wire are inserted. In Fig. 11 is shown a modified construction, in which oppositely disposed channels 28 are employed, permitting the ends of the wire to be inserted from opposite sides of the seal body; and in Fig. 65 12 is shown a single channel 29 adapted to

receive one end of the headed wire, the other end being embedded within the material of the seal body.

The principle of operation is the same in Figs. 9, 10, 11 and 12 as that described in 70 connection with the forms shown in Figs. 3 to 8 inclusive, and a detailed description thereof is not deemed necessary.

The method of using the seal is as follows: One headed end of the wire is inserted 75 in position in the manner described above, the free end of the wire is then inserted through the staple of the lock and the wire bent back on itself to form a loop. The other headed end is then inserted, as shown 80 in Fig. 7. Both free ends of the wire will then be anchored within the interior of the seal, and removal of the seal from the lock rendered impossible, except by a cutting of 85 the wire or a breaking of the seal body. 85

I claim:

1. A car seal, comprising a body portion having a channel therein adapted to permit of the insertion therethrough of the headed end of a wire, a headed wire, the wall of the 90 channel being partially cut away adjacent to the terminus thereof to provide a ledge, said wall being wholly cut away at the terminus thereof to provide a pocket, the inner edge of the ledge forming the outer wall of 95 the pocket, the headed end of the wire, when fully inserted, lying within said pocket, the body portion of the wire extending across and above said ledge, said ledge forming a protuberance in said channel whereby, after 100 the headed end of the wire has been entered into the pocket, movement of the wire to withdraw said headed end from said pocket is prevented, substantially as described.

2. A car seal comprising a body portion 105 having a chamber formed therein, provided with oppositely curving walls, a headed wire, a protuberance adjacent the outer end of said chamber, the walls of said protuberance being formed to correspond with the 110 walls of said chamber, whereby companion, oppositely disposed channels are provided, and adapted to receive the headed end of a wire, the walls of the channel being on a curve extending from the center in either 115 direction toward the center of the sealed body and serving to place a tension on the wire during the insertion therethrough, the walls of said chamber adjacent the inner end thereof being partially cut away to provide 120 ledges, that portion of the chamber behind said ledges forming pockets in which the headed ends lie when fully inserted, the body portion of the wire lying across the ledge when the headed end is fully inserted 125 within the pocket, the walls of the mouth and outer protuberance co-operating to prevent movement of the wire tending to withdraw the headed end from the pocket, substantially as described. 130

3. A car seal comprising a body portion having a channel therein adapted to permit of the insertion therethrough of the headed end of a wire, a headed wire, the wall of the channel being partially cut away adjacent the terminus thereof to provide a ledge, said wall being wholly cut away at the terminus thereof to provide a pocket adapted to receive the headed end of the wire, the inner wall of the ledge forming the outer wall of the pocket, the headed end of the wire lying when fully inserted within said pocket, the body portion of the wire extending across and above the surface of the ledge, the walls of said channel being in the form of a curve whereby the wire is placed under a tension during its insertion through said channels.

4. A car seal comprising a body portion having companion channels of similar formation oppositely disposed from one another, each adapted to permit of the insertion therethrough of the headed end of a wire, a headed wire, the wall of the channel being partially cut away adjacent the terminus thereof to provide a ledge, said wall being wholly cut away at the terminus thereof to provide a pocket adapted to re-

ceive the headed end of the wire, the inner edge of the ledge forming the outer wall of the pocket, the headed end of the wire lying when fully inserted within said pocket, the body portion of the wire extending across and above the surface of the ledge, said channels each being in the form of a curve whereby the wire is placed under a tension during its insertion therethrough, substantially as described.

5. A car seal comprising a body portion having a channel therein, a wire having a headed end adapted to be inserted through the channel, a protuberance extending into the channel intermediate the ends of the channel, and of less height than the depth of the channel, a pocket to the rear of the protuberance and forming the terminus of the channel, the headed end of the wire lying within said pocket and behind said protuberance when fully inserted in said body portion, the body portion of the wire extending across and above said protuberance, substantially as described.
